NAIL

William A. Wisckol, Detroit, Mich., assignor to
 Douglas & Lomason Co., Detroit, Mich., a corporation of Michigan

Application September 17, 1942, Serial No. 458,691

10 Claims. (Cl. 36—59)

This invention relates to nails, sometimes termed "alpine" nails, adapted to be fastened to the soles of shoes or boots used in mountain or glacial regions and designed for anti-skid purposes on any icy or similar slippery surfaces.

An object of the present invention is to provide an alpine nail for a boot or shoe which is formed from a single metal blank and is provided with integral means, such as prongs, for attaching the device to the sole of the boot or shoe.

A further object of the invention is to provide a nail or anti-skid cleat-like device attachable to the sole of a boot or shoe by means of fish hook prongs formed integrally from a single metal blank which in turn is provided with anti-skid means to prevent slipping on icy or other similar surfaces.

Still another object of the invention is to provide an anti-skid alpine nail attachable to the sole of a boot or shoe and economically formed in improved manner from a single metal blank by stamping and/or punch press operations.

A further object of the invention is to provide an improved alpine or anti-skid nail which is generally V-shaped in cross-section, having jagged or saw-tooth edges for anti-skid purposes and also having integral means by which the device may be attached directly to the bottom of a boot or shoe sole.

A still further object of the invention is to provide a V-shaped nail of the foregoing character provided with attaching prongs adapted to be driven into the sole of the shoe and preferably formed so as to anchor themselves in the sole against ready withdrawal.

Another object of the invention is to provide an alpine nail of the foregoing character provided with hook-like prongs adapted to be driven into the shoe sole to anchor the device therein.

Other objects of this invention will appear in the following description and appended claims, reference being had to the accompanying drawing forming a part of this specification wherein like reference characters designate corresponding parts in the several views.

Fig. 1 is a view of a boot or shoe carrying anti-skid nails embodying the present invention.

Fig. 2 is an enlarged section through the sole and nail.

Fig. 3 is a bottom plan view of the boot or shoe of Fig. 1.

Fig. 4 is a perspective view of the nail or anti-skid device.

Fig. 5 is a view of a flat punched blank before certain bending operations.

Fig. 6 is a rear elevation of the device.

Fig. 7 is a plan view of the device.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation.

In the drawing there is illustrated a present preferred form of an anti-skid nail or device, generally designated at A, constructed in accordance with the present invention. The nail is preferably formed from a single blank of relatively heavy gauge sheet steel, see Fig. 5, and is designed for attachment to the bottom of the sole 20 B of a mountain boot or shoe C.

The nail illustrated in accordance with the present embodiment of the invention is V-shape in cross-section comprising sides 10 and 11 integrally formed from a single metal blank and extending at an acute angle with respect to each other to provide a pointed wedge.

As illustrated in Fig. 5, the blank in the flat may be punched out or cut away at 12 and 13 to provide projecting prongs 14, 14a and 14b. Preferably two of the prongs 14 and 14a extend from one half of the blank, with the cut-away portion 12 somewhat wider than the cut-away portion 13.

The lower edge of the blank is blanked out to provide a jagged or saw-tooth edge 15. A portion 35 of the metal between the prongs 14 and 14a is left to form a tongue 16 having a hole 17 for the reception of a fastening element. The outer edges of the prongs 14, 14a and 14b are notched at 18 and the ends are wedge-shaped or pointed at 19. 40 The blank, illustrated in Fig. 5, may be bent along the dotted line 20 into V-shape with the two prongs 14 and 14a extending from the side 10 and the single prong 14b extending from the side 11. In this same operation, or at any other operation in the formation of the device, the tongue 16 may be bent inwardly along the dotted line 21 so as to extend at right angles to the side 10.

The nail, thus formed as shown in Figs. 4, 6 and 7, may be attached to the sole of the boot or shoe C in the manner illustrated in Figs. 2 and 3. The prongs are driven into the sole, burying the hook-like ends in the leather. By virtue of the notches 18 the prongs in effect function similarly to fish-hooks and securely anchor themselves in the sole against ready removal. When

the nail is driven fully into the sole, as shown in Fig. 2, the tongue 16 abuts or comes up against the bottom of the sole. To insure unquestionable anchoring of the nail to the sole against any danger of displacement or loosening during hard usage, a brad or other ordinary nail or fastening element 22 is driven through the hole 17 into the shoe sole and clinched over, if desired, to prevent withdrawal.

An alpine nail constructed in the foregoing described manner has considerable advantages in usage, being strong and durable, and constructed to afford excellent gripping or anti-skid qualities on icy or slippery surfaces. In addition, it may be economically manufactured from a single metal blank and easily attached to the sole of the boot or shoe.

I claim:

1. An anti-skid boot or shoe nail formed from a single metal blank comprising a generally V-shaped body having jagged lower edges, integral prongs adapted to be driven into the sole of the shoe and a projecting part lying between the sides of the body and overlying said sole.

2. An anti-skid boot or shoe nail formed from a single metal blank comprising a generally V-shaped body having jagged lower edges and integral prongs adapted to be driven into the sole of the shoe, and an attaching tongue struck from the metal of one side of the body and apertured to receive a fastening element adapted to be driven into the sole.

3. An anti-skid boot or shoe nail formed from a single metal blank comprising a generally V-shaped body having jagged lower edges and integral prongs adapted to be driven into the sole of the shoe, and an attaching tongue struck from the metal of one side of the body and apertured to receive a fastening element adapted to be driven into the sole, said tongue extending at substantially right angles to the body and within the space between the sides thereof.

4. An anti-skid boot or shoe nail comprising a body having angularly related sides formed from a single metal blank, the lower edges of said sides having teeth, the upper edges having projecting pointed prongs adapted to be driven into the shoe sole, and one of said sides having an inwardly projecting portion adapted to engage the sole.

5. An anti-skid boot or shoe nail comprising

a body having angularly related sides formed from a single metal blank, the lower edges of said sides having teeth, the upper edges having projecting pointed prongs adapted to be driven into the shoe sole, and one of said sides having an inwardly projecting portion to engage the sole and apertured to receive a fastening element.

6. An anti-skid boot or shoe nail comprising a body having angularly related sides provided with projecting prongs adapted to be driven into the shoe sole, and an attaching tongue formed from the metal intermediate said prongs and positioned to overlie the shoe sole.

7. An anti-skid boot or shoe nail comprising a body forming angularly related sides terminating at their inner edges in prongs, adapted to be driven into the shoe sole and having intermediate said prongs a laterally extending sole engaging portion.

8. An anti-skid boot or shoe nail comprising a cross-sectionally wedge-shaped body forming angularly related sides terminating at their outer edges in jagged portions, said sides having projecting prongs adapted to be driven into the shoe sole, said sides also having a tongue struck from the metal of one side at right angles thereto and adapted to abut against the bottom of the sole, said tongue having an aperture for the reception of a fastening element.

9. An anti-skid boot or shoe nail comprising a cross-sectionally wedge-shaped body forming angularly related sides terminating at their outer edges in jagged portions, said sides having one a single projecting prong and the other a pair of projecting prongs adapted to be driven into the shoe sole, and a laterally extending member formed from the metal between said last named prongs.

10. An anti-skid boot or shoe nail comprising a cross-sectionally wedge-shaped body forming angularly related sides terminating at their outer edges in jagged portions, said sides having one a single projecting prong and the other a pair of projecting prongs adapted to be driven into the shoe sole, said sides also having a tongue struck from the metal of one side at right angles thereto and adapted to abut against the bottom of the sole, said tongue having an aperture for the reception of a fastening element.
